UNITED STATES PATENT OFFICE.

ALFRED M. REMINGTON, OF FITCHBURG, MASSACHUSETTS, ASSIGNOR TO SIMONDS MANUFACTURING COMPANY, OF FITCHBURG, MASSACHUSETTS, A CORPORATION OF MASSACHUSETTS.

METHOD OF FORMING THE CLASPS OF THE INTERLOCKING PORTIONS OF EXTENSIBLE FRAMES FOR SAW-BLADES OR OTHER TOOLS.

No. 928,217.

Specification of Letters Patent.

Patented July 13, 1909.

Application filed August 10, 1908. Serial No. 447,708.

To all whom it may concern:

Be it known that I, ALFRED M. REMINGTON, a citizen of the United States of America, residing at Fitchburg, in the county of Worcester and State of Massachusetts, have invented an Improved Method of Forming the Clasps of the Interlocking Portions of Extensible Frames for Saw-Blades or other Tools, of which the following is a specification.

The invention relates to the method of forming upon the ends of the two portions of extensible frames, the loops or clasps which interlock and slide over the respective parts; and it consists in slitting the end of the metal bar which is to form each portion of the frame, spreading the two portions of the slitted end in opposite directions until they stand at rights to the length of the strip, but in the same plane as the width of the strip, bending these two spread ends at right angles to said plane, interlocking the bent ends of each portion of the frame with the companion strip of metal and finally bending such ends of each over the portion of the frame with which they are interlocked.

This method is especially adapted for making the loops or clasps for the interlocking portions of extensible frames for saw-blades such as hack and butchers' saws.

In the drawings where the several steps of the method are illustrated, Figure 1 shows a bar with the end slitted; Fig. 2, the slitted ends bent at right angles to the length of the bar; Fig. 3, those ends bent at right angles to the width of the bar; Fig. 4 shows such ends

interlocked with and bent over the companion strip or bar of metal; Fig. 5 shows the ends of the two portions of an extensible saw-frame interlocked by clasps made according to my method.

The bar of steel B is slitted at s; the ends e, e, on each side of the slit are bent outward at right angles to the length of the bar, in the same plane with its width, these ends are again bent at right angles to the width of the bar, as shown in Fig. 3, and after the respective ends, thus bent, have been interlocked with the companion bar of the extensible frame, they are bent over and thus clasped about such portion, forming loops which may slide upon the portion of the bar which they clasp, as illustrated in Figs. 4 and 5.

When metal of suitable quality is employed, the method may be practiced upon it without heating the bars.

I claim:

The method of making extension saw-frames, which consists in slitting one end of the respective metal strips to be interlocked, spreading the two portions of the slitted ends at right angles to, and in the same plane as the width of the strip, bending the two spread ends at right angles to the said plane, interlocking the bent ends of each portion with the companion strip and bending such ends together over the strip with which they are interlocked.

ALFRED M. REMINGTON.
